UNITED STATES PATENT OFFICE.

ROBERT PEBERDY, OF PHILADELPHIA, PENNSYLVANIA, ASSIGNOR TO
JAMES CREIGHTON, OF SAME PLACE.

IMPROVEMENT IN KNITTING-MACHINE.

Specification forming part of Letters Patent No. 87,508, dated March 2, 1869.

To all whom it may concern:

Be it known that I, ROBERT PEBERDY, of Philadelphia, Pennsylvania, have invented a certain Improvement in Knitting-Machines; and I do hereby declare the following to be a full, clear, and exact description of the same.

My invention consists of two or more sets of self-acting or latch needles arranged in a straight-frame knitting-machine, as fully described hereafter, and in combination with two or more sets of thread-guides, and with devices whereby the needles may be adjusted laterally during the operation of the machine, so as to produce ornamental fabrics of various patterns.

In order to enable others skilled in the art to make and use my invention, I will now proceed to describe its construction and operation, reference being had to the accompanying drawing, which forms a part of this specification, and in which—

Figure 1 is a side elevation of my improved knitting-machine; Fig. 2, the same, showing the parts in a different position; and Fig. 3, a sectional elevation on the line 12, Fig. 1.

A A' are the side frames of the machine, which are secured to a suitable base-plate, and are connected at the top by a cross-bar, B, and to the latter is hung a swinging frame, C, in which slide the usual guide-bars a a', carrying each a series of guides, b. To the side frames are connected the ends of two parallel stationary knocking-over bars, c c', the space between which is just sufficient for the passage of the fabric. Adjacent to the outer sides of the bars c c' slide the needle-bars d d', to which are secured the usual latch-needles e, the bars d d' being so connected to operating parts of the machine that they will have a vertical reciprocating motion, one bar rising as the other descends. Some of the needles e on the bar d are removed, to allow for the introduction to the row on the said bar of needles i i', secured to rods f f', sliding in projections g g' on the bar d, the rod f being bent so that its axis shall be above the upper ends of the needles e, for a purpose described hereafter.

To a cranked portion of the rod f is jointed one end of a rod, k, which is connected at the opposite end to a lever, E, hung to a bracket secured to the base-plate of the machine, and against the inner end of this lever bears a cam,

h, on a shaft, D, turning in the side frames, A A'. The rod f, lever E, and cam h are so constructed, arranged, and connected to the operating parts of the machine that as the bar d approaches the limit of its upward motion the rod f will be caused to swing outward, and thus carry its needles i beyond the needles e i', as shown in Fig. 3.

Each of the rods f f' is connected to devices operated by a Jacquard apparatus or by a pattern-wheel, so that a simultaneous sliding motion in opposite directions may be imparted to the said rods when the bar d is at the limit of its upward movement, and the operating parts of the machine are connected to any suitable devices for imparting the usual movements to the same, the construction and arrangement of these devices being too familiar to those skilled in this class of machinery to require illustration or description.

The threads are conveyed to the guides b, and are placed in loops on the needles in the ordinary manner, when the operation of the machine will be as follows: When either of the bars d d' is at the limit of its upward motion, the guides above this bar will be so operated that a thread will be conducted across the front edge of each needle, the needle-bar will then descend, and the thread opposite each needle will be caught by the hook of the latter, and will be drawn downward through the old loop on the needle, which hangs over the edge of the bar c, closes the latch as the needle descends, and finally slips off the end of the needle, and onto the new loop. The threads are now conducted across the needles of the opposite bar, which has risen to the limit of its upward motion, and a series of new loops is formed on the needles of this bar, in the manner already described.

So long as these operations continue, an ordinary ribbed fabric will be produced. When, however, an ornamental fabric is to be formed, a simultaneous sliding motion in opposite directions is imparted to the rods f f' after the bar d arrives at the limit of its upward motion, when the needles i i' will change places, the needles i' moving from the position shown in Fig. 1 in the direction of the arrow to the positions shown in Fig. 2, which were at first occupied by the needles i, the latter simulta-

neously moving in the opposite direction, and taking the positions first occupied by the needles i' , the rod f , before these movements, having been carried outward, by the operation of the cam E , to the position shown in Fig. 3, so that the needles i , prior to their lateral movement, will be carried beyond the path of the needles i' . Owing to this change in the position of the needles, the threads will be crossed in such a manner as to produce a variation in the stitch, and an alteration in the character of the fabric, the extent and nature of alteration being determined by the character of the Jacquard cards, or the shape of the pattern-wheel, and the arrangement of the needles.

In some instances three or more rods, carrying three or more sets of needles, may be used, and these adjustable needles may be so arranged as to produce either a fabric ornamented throughout its entire width or only at the border.

When it is desired to produce a fabric ornamented on both sides, the needles of the bar d' may be arranged to operate in the same manner as those of the bar d .

Without claiming, broadly, the combination, on one frame, of two sets of needles, adjustable laterally, independently of each other,

I claim as my invention and desire to secure by Letters Patent—

1. The combination of two or more series of self-acting needles, arranged in a row and adjustable laterally independently of each other, and a series of guides, b , operating in connection with the needles, substantially as described.

2. The combination of the above, the two parallel knocking-over bars $c c'$, and a second series of needles and another series of guides, the whole being arranged and operating substantially as specified.

In testimony whereof I have signed my name to this specification in the presence of two subscribing witnesses.

ROBERT PEBERDY.
